UNITED STATES PATENT OFFICE.

WILLIAM C. STEVENS, OF SUMMIT, NEW JERSEY, ASSIGNOR TO THE CUTLER-HAMMER MFG. CO., OF MILWAUKEE, WISCONSIN, A CORPORATION OF WISCONSIN.

HOISTING SYSTEM.

1,267,820.

Specification of Letters Patent. Patented May 28, 1918.

Application filed March 2, 1916. Serial No. 81,737.

To all whom it may concern:

Be it known that I, WILLIAM C. STEVENS, a citizen of the United States, residing at Summit, in the county of Union and State 5 of New Jersey, have invented new and useful Improvements in Hoisting Systems, of which the following is a full, clear, concise, and exact description, reference being had to the accompanying drawing, forming a part 10 of this specification.

This invention relates to hoisting systems.

It has been proposed to employ for dock hoists and other purposes a motor drive including a set of power transmitting gears, 15 between the driving motor and hoist drum; one gear of said set having play to apply a mechanical brake to the hoisting drum when the load in descending overhauls the motor and this invention is particularly applicable 20 to such hoisting systems.

One of the objects of the invention is to provide a system of this character with dynamic braking means to assist the mechanical braking means for a more efficient and accurate control of descending loads. 25

Further objects are to provide means whereby the dynamic braking means will be rendered inactive during hoisting operation of the driving motor and active at all times 30 when braking is needed and to provide for regulation of the dynamic braking action of such means for increased flexibility of control.

Other objects and advantages will herein- 35 after appear.

The accompanying drawing schematically and diagrammatically illustrates one embodiment of the invention which will now be described, it being understood that the 40 invention may be embodied in other forms falling within the scope of the appended claims.

The drawing schematically illustrates a winding drum 1, a cable 2 and a weight 3 attached to said cable and representing the load to be controlled. The drum is keyed to a shaft 4 and to be driven through a set of gears 5 by a motor M supplied from a three phase alternating current line L, L', L² 45 through a controller C. The gear set 5 includes a pinion 7 fixed to the motor shaft 6, two or more coaxial pinions 8 carried by a spider 9 fixed to the drum shaft 4 and a toothed ring 10 surrounding the aforesaid 50 pinions and meshing with the pinions 8. The

ring 10 is carried by a spider 11 revolubly mounted on the hub of spider 9 to have rotary play, limited by a fixed stop 12 in the path of a lug 13 on said spider 11. With the spider 11 locked by the stop 12 the gears 60 become effective as a driving medium between the motor and drum, while if the load in descending overhauls the motor, said drum through its pinions 8, will reverse the strain upon and rotate the ring 10, and it is 65 this movement of the ring which is utilized to mechanically brake the drum. As illustrated, the mechanical braking means includes a pivoted brake lever 14 to engage an annular brake surface 15 of the drum and 70 operable by a lever 16 projecting into the path of a lug 17 on the spider 11. The arrangement is such that when the spider 11 occupies its locked position against stop 12 the lug 17 on said spider clears the brake 75 actuating lever 16 whereas said lug is thrown against said lever when the spider moves from its locked position. Such is the hoisting apparatus referred to at the outset and as usual an electromagnetically controlled 80 brake 18 is provided to be set whenever the controller C is set in neutral position.

Referring now to the dynamic brake producing means, the same comprises a generator G having its armature coupled to the 85 shaft 6 of motor M to be driven thereby whenever the motor is in operation or is driven mechanically by a descending load. The field of this generator is supplied from a direct current line L-L' while its armature 90 terminals 19 and 20 are provided with a bridge including a resistance 21, said bridge being controlled by an electro-responsive switch 22. As will hereinafter appear, this switch is utilized to interrupt the armature 95 bridge during hoisting and to close the same during descent of the load, thereby insuring dynamic action of the generator under the desired conditions while relieving the hoisting machine of the braking action of 100 said generator when not required. Further, the generator is provided with a variable field resistance 23 whereby its dynamic braking action may be regulated at will and this resistance is controllable by the controller C. 105

The controller C is schematically illustrated as of the drum type and has two sections c and c' operable together to respectively control the alternating current circuits and the direct current circuits. The section c 110

comprises two sets of stationary contact fingers 30 to 34 and 35 to 43, the former having two sets of segments coöperating therewith to control the primary circuit of the motor M for reverse operations of said motor and the latter having two sets of segments coöperating therewith to control resistances R in the secondary circuit of the motor. Segments 30^a to 33^a coöperate with contacts 30 to 33 respectively to close the primary circuit of the motor for hoisting and segments 35^a to 43^a serve to exclude the resistances R from the secondary circuit of the motor in steps upon movement of the controller in hoisting direction for hoisting. Segments 31^b to 34^b coöperate with contacts 31 to 34 upon reverse or lowering operation of the controller to complete the primary circuit of the motor M for reverse operation thereof, or, in other words, operation to drive the load in its descent. Segments 37^b, 40^b and 43^b coöperate with contacts 37, 40 and 43 upon such operation of the controller to exclude all of the resistances R in one step but only when the controller is moved to its extreme lowering position. The connections are so obvious as to require no specific description thereof and from the foregoing it will be observed that when the controller is moved in hoisting direction, as indicated by the arrow, it will start and gradually accelerate the motor M and that when the same is moved in lowering direction it will establish power connections for the motor but will maintain all resistance in the primary circuit for slow speed of the motor unless it be thrown to its extreme position. Further, it will be observed that in neutral position of the controller all segments disengage their respective contacts.

The part c' of the controller has two sets of contacts 44 to 48 and 50—51, the former being connected to the field resistance 23 of the generator G and the remaining two contacts being respectively connected to the coils of the electro-mechanical brake and switch 22. Contact 44 is connected directly to line L and has a permanently engaging segment 44^b while the contacts 45 to 49 have coöperating segments 45^b to 48^b connected to segment 44^b and arranged to short-circuit the resistance 23 in the off position of the controller and to include said resistance in circuit by steps when the controller is moved in lowering direction. When the controller is moved in hoisting direction the contact 48^b is immediately withdrawn from engagement with contact 48 thereby including the entire resistance 23 in the field circuit of the generator. Contact 50 has coöperating segments 50^a and 50^b both connected to segment 44^b to energize the electro-mechanical brake upon and throughout movement of the controller in either direction from neutral position. Contact 51 has a coöperating segment

51^a connected to segment 44^b to energize coil of switch 22 upon and throughout movement of the controller in hoisting direction. Also, contact 51 has a coöperating segment 51^b to engage therewith upon lowering movement of the controller to energize the coil of switch 22 but only in the extreme lowering position of the controller.

More particularly describing the D. C. circuits that of the generator field may be traced from line l to contact 44, through all or less of resistance 23 according to the position of the controller, by conductor 55 to one field terminal of the generator, while the return may be traced from the other field terminal by conductor 56 to line l'. When the controller is moved to either side of neutral position a circuit is also established from line l to conductor 44 and segments 44^b to segments 50^a and 50^b and from one of said segments to contact 50 by conductor 57 through the coil of the electro-mechanical brake to conductor 56 and thence to line l. Finally the energizing circuit of switch 22 may be traced from line l to contact 44 and segment 44^b to segments 51^a and 51^b and from one of said segments to contact 51 by conductor 58 through the winding of switch 22 to conductor 56 and thence to line l'.

Considering now the system as a whole, when the controller is in off position the motor M is disconnected from circuit while the electro-mechanical brake is deenergized and hence applied. Also, in the off position of the controller the field of the generator is included in circuit with all of its field resistance excluded and the switch 22 is deenergized to bridge the armature terminals of the generator. Thus connected the generator is in condition to exert its maximum braking force and hence off position of the controller represents the position in which the controller should be set for maximum braking action for a descending load.

Assuming now that it is desired to lower a light load without braking action, the controller is moved to its extreme lowering position to thereby connect the motor M in circuit and exclude all resistance from the rotor circuit. Under such conditions segment 51^b coöperates with contact 51 to energize switch 22 thereby interrupting the bridge across the terminals of the generator and eliminating all braking action of the generator. On the other hand, if the load when started tends to descend too rapidly then the same may be checked to the desired degree by moving the controller toward off position. The first step of movement in this direction disengages segment 51^b from contact 51 thereby deenergizing switch 22 with consequent closure thereof to reestablish dynamic braking connections for the generator. However, in this position of the

controller the entire resistance 23 is included in the field circuit of the generator whereby the braking effect of the generator is materially curtailed, but by continued movement 5 of the controller the resistance may be gradually excluded from circuit to increase the field strength of the generator and hence increase its braking effect. Finally the controller may be returned to off position with 10 the result of disconnecting the motor from circuit and establishing connections for maximum braking effect of the generator.

Thus it will be observed that under descending load conditions the braking duty 15 is divided between the mechanical and dynamic brakes and that with the dynamic brake regulation described an exceedingly efficient, reliable and flexible control is provided.

20 While it is unnecessary to specifically consider the conditions obtained by moving the controller in hoisting direction, it should here be noted that upon such movement of the controller the segment 48^b disengages 25 segment 48 thereby inserting the entire resistance 23 in circuit with the generator field. This effects an economy of current and protects the generator which under hoisting conditions operates without armature connections.

What I claim as new and desire to secure 20 by Letters Patent is:

1. In a hoisting system, in combination, 35 a hoisting machine, a generator to be driven thereby, a normally closed dynamic braking circuit for said generator and jointly operable control means for said machine and generator insuring interruption of said dynamic braking circuit upon starting of said 40 machine for hoisting and insuring reestablishment of said dynamic braking circuit upon starting of said machine for lowering.

2. In a hoisting system, in combination, 45 a hoisting machine, a generator to be driven thereby, a normally closed dynamic braking circuit for said generator and jointly operable control means for said machine and generator insuring interruption of said dynamic braking circuit upon starting of said 50 machine for hoisting and insuring reestablishment of said dynamic braking circuit upon starting of said machine for lowering but enabling subsequent interruption of said dynamic braking circuit for unretarded lowering operation of said machine.

3. In a hoisting system, in combination, 60 a hoisting machine, a generator to be driven thereby, a normally closed dynamic braking circuit for said generator and jointly operable control means for said machine and generator insuring interruption of said 65 braking circuit upon starting of said machine in hoisting direction and reestablishment of said circuit upon starting of said machine in lowering direction, said control

means further providing for regulation of said generator to vary its dynamic braking effect and for interruption of said dynamic braking circuit while said machine is continued in operation in a lowering direction. 70

4. In a hoisting system, in combination, 75 a hoisting mechanism, a driving machine therefor, a mechanical brake for said mechanism, driving connections between said machine and said mechanism acting upon said brake to apply the latter under overhauling load conditions, a generator to be driven by said machine, a normally closed dynamic braking circuit for said generator, and jointly operable control means for said machine and generator. 80

5. In a hoisting system, in combination, 85 a hoisting mechanism, a driving machine therefor, a mechanical brake for said mechanism, driving connections between said machine and said mechanism acting upon said brake to apply the latter under overhauling load conditions, a generator to be driven by said machine, a normally closed dynamic braking circuit for said generator, and jointly operable control means for said machine and generator insuring interruption of said dynamic braking circuit upon starting of said machine for hoisting and enabling operation of said machine in lowering 90 direction with said dynamic braking circuit either completed to assist said mechanical brake or interrupted to relieve said machine of its retarding effect, leaving the braking duty to said mechanical brake. 95

6. In a hoisting system, in combination, 100 a hoisting mechanism, a driving machine therefor, a mechanical brake for said mechanism, driving connections between said machine and said mechanism acting upon said brake to apply the latter under overhauling load conditions, a generator to be driven by said machine, a normally closed dynamic braking circuit for said generator, and jointly operable control means for said machine and generator, insuring interruption of said dynamic braking circuit upon starting of said machine for hoisting and enabling operation of said machine in lowering 105 direction with said dynamic braking circuit either completed to assist said mechanical brake or interrupted to relieve said machine of its retarding effect, leaving the braking duty to said mechanical brake, said control means also providing for regulation 110 of said generator, when its dynamic braking circuit is closed, to vary the dynamic braking effect thereof. 115

7. In a controller for hoisting machines, 120 in combination, a reversible power controller for the hoisting machine, a generator to be driven by the machine and having a dynamic braking circuit, a switch biased to close the braking circuit of said generator and having a winding to operate the same to 125 130

- 4
- interrupt said circuit and control means for said switch operable with said power controller, said switch controlling means insuring energization of said switch in all hoisting positions of said power controller and insuring deenergization of said switch in the neutral position of said power controller and upon movement of said controller to its first lowering position.
  - 10 8. In a controller for hoisting machines, in combination, a reversible power controller for the hoisting machine, a generator to be driven by the machine and having a dynamic braking circuit, a switch biased to close the 15 braking circuit of said generator and having

a winding to operate the same to interrupt said circuit and control means for said switch operable with said power controller, said switch controlling means insuring energization of said switch in all hoisting positions of said power controller and insuring deenergization of said switch in the neutral position of said power controller while providing for selective energization and deenergization of said switch in lowering position 25 of said power controller.

In witness whereof I have hereunto subscribed my name.

WM. C. STEVENS.
